R. E. DOEDEN

Des. 168,215

PNEUMATIC TOOL UNIT

Filed Dec. 14, 1951

Inventor:

Roland E. Doeden

UNITED STATES PATENT OFFICE

168,215

PNEUMATIC TOOL UNIT

Roland E. Doeden, Crete, Ill., assignor to Mall
Tool Company, Chicago, Ill., a corporation of
Illinois

Application December 14, 1951, Serial No. 17,739

Term of patent 14 years

(Cl. D54—14)

To all whom it may concern:

Be it known that I, Roland E. Doeden, a citizen of the United States, residing at Crete, State of Illinois, have invented a new, original, and ornamental Design for Pneumatic Tool Unit, of which the following is a specification, reference being had to the accompanying drawing, forming a part hereof.

Fig. 1 is a side elevation view of a pneumatic tool unit showing my new design;

Fig. 2 is a top plan view of the unit shown in Fig. 1;

Fig. 3 is a front end view of the unit shown in Fig. 1;

Fig. 4 is a rear end view of the unit shown in Fig. 1.

I claim:

The ornamental design for a pneumatic tool unit, as shown.

ROLAND E. DOEDEN.
